UNITED STATES PATENT OFFICE.

HORACE McCAFFREY, OF DALLAS, TEXAS.

SCREEN-FASTENER.

1,369,036.

Specification of Letters Patent. Patented Feb. 22, 1921.

Application filed June 10, 1920. Serial No. 387,962.

To all whom it may concern:

Be it known that I, HORACE McCAFFREY, a citizen of the United States, residing at Dallas, in the county of Dallas and State of Texas, have invented a new and useful Screen-Fastener, of which the following is a specification.

This invention relates to screen structures, and it is the primary object of the invention 10 to provide novel means for securing the wire mesh of the screen to the frame thereof, to prevent accidental displacement of the screen from its supporting frame.

A further object of the invention is to 15 provide means of this character to maintain the wire mesh taut in a manner to eliminate sagging thereof.

A still further object of the invention is to provide a gaging means forming a part 20 of the securing means for insuring the wire mesh material being held in proper relation with the securing means.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed, may be made within the scope of what is claimed, without departing from the spirit of the invention.

Referring to the drawing:—

Figure 1 illustrates a fragmental view of 35 a screen constructed in accordance with the present invention.

Fig. 2 illustrates a sectional view taken on line 2—2 of Fig. 1; and

Fig. 3 illustrates a sectional view taken on 40 line 3—3 of Fig. 1.

Referring to the drawing in detail, the reference character 5 designates the frame of the machine formed preferably of wood and to which the wire mesh screen indicated 45 at 6, is secured.

The securing means forming the subject matter of the present invention includes the metallic strips indicated generally by the reference character 7, each of which includes a body portion and an offset portion 50 forming a part thereof, and which offset portion 8 provides a bead 9, for securing the body in spaced relation to the frame to which the same is attached, to lend resiliency 55 to the securing strips.

Stamped from the body portion of the se-

curing means, are the pointed securing spurs 10 arranged in staggered relation with each other and bent downwardly to pass between the mesh of the screen, to which the securing 60 means is applied, and embed themselves in the material of the frame, as indicated by Fig. 3 of the drawing, and since the spurs are disposed substantially throughout the entire lengths of the securing means, it is 65 obvious that the wire mesh material is held against displacement, there being provided securing nails indicated at 11 for fastening the securing means to the frame.

Associated with the securing spurs 10, are 70 the inwardly extending gaging arms 10', which are also stamped from the material forming the sections, and are designed to engage the edge of the wire mesh material to restrict movement thereof, with relation to 75 the body portion of the securing means.

The securing strips 7 are connected at the ends or corners of the frame by means of the corner plates 9', which also have offset portions 8' contacting with the frame, the ends 80 of the corner plates overlapping the adjacent ends of the securing strips, as at 15, whereby the securing strips and corner plates are fastened to the frame of the screen. 85

The wire mesh material 6 is secured to the central or cross bar 5' of the frame, as by means of the securing strip 12, which is also provided with the depending spurs 13, that extend through the wire mesh material to 90 prevent movement of the wire screen with relation to the cross bar 5', the securing strip 12 being secured to the bar 5' by means of the nails 14, passing through suitable openings in the strip 12. 95

Having thus described the invention, what is claimed as new is:—

1. In combination with the frame and wire mesh material supported thereby, a securing means including metallic strips, each of 100 said metallic strips having integral depending spurs adapted to pass through the wire mesh, gaging arms associated with the spurs to contact with an edge of the wire mesh material, and means for securing the strips 105 to the frame.

2. In combination with the frame and wire mesh material supported thereby, a securing means including metallic strips adapted to be positioned on the wire mesh 110 material, means for securing the metallic strips to the frame, means carried by the

strips and passing through the wire mesh material, for securing the wire mesh material to the strips, and means formed integral with the strips and contacting with the edges of the wire mesh material for restricting lateral movement of the wire mesh material with relation to its frame.

3. A securing means for securing wire mesh material to a frame, said securing means including metallic strips, said strips having spurs punched therefrom, and depending from one of the side faces thereof, said spurs adapted to pass through the mesh of the wire mesh material, gaging arms 10 formed integral with the strips and depend-

ing therefrom, said gaging arms adapted to embrace the edges of the wire mesh material for preventing lateral movement thereof, with relation to the frame, and corner plates secured to the frame, the corner plates having portions thereof overlapping adjacent ends of the plates. 20

In testimony that I claim the foregoing as my own, I have hereto affixed my signature in the presence of two witnesses.

HORACE McCAFFREY.
